US00D815861S

(12) **United States Design Patent** (10) Patent No.: **US D815,861 S**
(45) Date of Patent: **** Apr. 24, 2018**

(54) **MEMORY PILLOW**

(71) Applicant: **Alivia Kassab Arabo**, West Bloomfield, MI (US)

(72) Inventor: **Alivia Kassab Arabo**, West Bloomfield, MI (US)

(**) Term: **15 Years**

(21) Appl. No.: **29/587,282**

(22) Filed: **Dec. 12, 2016**

(51) LOC (11) Cl. **06-09**

(52) U.S. Cl.

USPC **D6/601**

(58) **Field of Classification Search**

USPC D6/333, 349, 355, 375, 388, 512, 563, D6/564, 595, 596, 601, 604, 611, 707, D6/715, 716, 716.1; D24/183–185, 234; D21/803, 804, 805, 809; 5/401, 420, 5/600, 630, 631, 632, 633, 635, 636, 638, 5/639, 646, 652, 652.1, 655, 703, 730; 297/1, 2, 4, 93, 180.11, 195.1, 195.11, 297/195.13, 393, 397, 452.12, 452.14, 297/452.15, 452.21, 452.24, 452.26, 297/452.48, 452.62, 482

CPC A47G 9/10; A47G 9/1009; A47G 9/1027; A47G 9/1045; A47G 9/1063; A47G 9/1072; A47G 9/1081

Primary Examiner — Eric L Goodman

Assistant Examiner — Sanjeev Paul

(74) Attorney, Agent, or Firm — Dinsmore & Shohl LLP

(57) **CLAIM**

The ornamental design for a pillow, as shown and described.

DESCRIPTION

FIG. 1 is a perspective of the present design;

FIG. 2 is a front view of the present design;

FIG. 3 is a right side view of the present design;

FIG. 4 is a left side view of the present design;

FIG. 5 is a rear view of the present design;

FIG. 6 is a top view of the present design; and,

FIG. 7 is a bottom view of the present design.

The broken lines shown in the drawings are included for the purpose of illustrating environmental structure and form no part of the claimed design.

1 Claim, 6 Drawing Sheets
